BLADE MAGAZINE

Nicholas Testi, Boston, Mass., assignor to Gillette Safety Razor Company, Boston, Mass., a corporation of Delaware

Application October 14, 1946, Serial No. 703,266

8 Claims. (CL. 206—16)

1

This invention relates to magazines or receptacles for safety razor blades of the type designed to contain a convenient number of blades disposed in a stack and held securely and without contact of the cutting edges of the blades with the walls of the receptacle while the blades are contained therein or while being withdrawn, one by one, for use.

The device of my invention may be employed as a reservoir for a supply of sharp blades by the user, or it may be employed as a dispensing receptacle in which the blades are packed by the manufacturer and distributed to the trade, or for both uses.

Heretofore, many blade magazines have been designed to eject a blade much as an empty shell is ejected from a magazine rifle. The snappy discharge of the blade pleases many users and encourages them to draw liberally on the supply of fresh blades in the magazine. However, this system has the objectionable feature that a sharp blade may be thrown or may fall upon the floor where it is likely to be overlooked by the user or picked up by children.

It has been proposed to overcome these disadvantages by providing means for temporarily holding each blade, as delivered, in convenient position after it has been separated from the other blades in the stack and projected from the magazine. For example, the blade may be held projecting into space so that the user may conveniently and safely, and whenever convenient, take hold of it for the purpose of placing it in his safety razor.

However, if the blade-ejecting feed slide is abruptly arrested at the end of its path while directly engaged by the fingers of the user, the fingers will slip forwardly from the feed slide and be cut by the edge of the blade as it projects from the end of the magazine. This danger is obviated in accordance with the present invention by providing the feed slide with an elongated operating handle of such length that it may be grasped by the fingers of the user in a location in advance of the end of the blade. If there is any slipping of the user's fingers from such a handle, it is in a direction away from the sharp edges of the blade instead of toward them. Where a handle of this kind is employed in a magazine which is constructed and arranged to deliver blades from both ends, the connection between the handle and the blade preferably includes means for causing the handle to assume a substantially horizontal position on one side or the other of the feed slide. This not only locates the handles conveniently for use in the blade-ejecting operation but keeps the magazine assembly in compact compass.

2

These and other features of the invention will be best understood and appreciated from the following description of a preferred embodiment thereof, selected for purposes of illustration and shown in the accompanying drawings, in which:

Figure 1 is a view of the magazine in perspective on an enlarged scale;

Fig. 2 is a view similar to Fig. 1 but showing the feed slide moved to another position; and

Fig. 3 is a corresponding end view.

The magazine herein selected for purposes of illustration is adapted particularly for use in connection with safety razor blades of a well-known commercial type; that is to say, thin, flexible blades .004 to .007 inch in thickness, longitudinally slotted, and having corner notches defining elongated unsharpened end portions in the blade as in the blades sold commercially under the trade mark "Gillette." It will be understood, however, that the invention is not limited to that or to any specific kind of blade but with appropriate modifications may be easily adapted to blades of other kinds, all within the scope of the invention.

The magazine herein shown comprises walls forming an elongated rectangular enclosure. These include a bottom 10, side walls 11 and 12, and inturned top flanges 13 and 14, which are spaced from each other and thus present a wide longitudinal opening. In the bottom of the enclosure is secured, by rivets or otherwise, a base plate 15 moulded of plastic material or formed of metal, as desired. From the base plate projects a central upstanding blade-locating rib 16 and a pair of flat blade-locating studs 17 arranged in alignment with the rib 16. Corner posts 18 also project upwardly from the base plate 15, and these terminate a short distance below the top flanges 13 and 14 so as to permit the endwise movement of a single blade above them sliding in contact with the flanges.

At each end of the enclosure and beyond the blade-locating studs 17 may be provided a fulcrum block 19 presenting an upper fulcrum surface 20 which slopes outwardly and upwardly from below the plane of the inner face of the top flanges 13 and 14 to a level above that plane. As herein shown, the fulcrum block is solid in construction and let into a recess formed for that purpose in the upper face of the base plate 15; but the construction of the fulcrum block is of secondary importance so long as it presents a fulcrum surface in the proper location and one which is wider than the blade slot. It might well be formed, for example, by striking up an angular tongue from the material of the base plate.

A forked or slotted spring 21 underlies the blade stack, holding it upwardly so that the uppermost

blade in the stack is pressed into contact with the lower faces of the flanges 13 and 14. By reason of its slot or fork, the spring 21 clears the rib 16 and the studs 17.

A feed slide 22 is arranged to slide longitudinally upon the magazine, having for this purpose side walls which embrace the side walls of the magazine. The bridge portion of the feed slide 22 may be provided with a pair of downwardly-extending ribs 23, so designed and arranged as to engage only the uppermost blade in the stack as the blade is accurately located at the level determined by the inturned flanges 13 and 14. Stop lugs 24 project from the flanges 13 and 14 and positively limit the movement of the feed slide 22 confining it to a path of a definite predetermined length.

The present magazine is of the general type of that shown in my prior Patent No. 2,359,807 in which the blades of the stack are arranged in longitudinally staggered relation. This is advantageous because it provides the maximum working space and clearance for the operation of the feed slide. It should be noted again, however, that the means for locating the blades of the stack and separating the individual blades in the feeding operation are matters of secondary importance only and may be widely varied within the scope of the invention.

In Fig. 1, the feed slide 22 is shown at one extremity of its path in readiness for movement toward the right to eject the uppermost blade 25 from the stack. The stack may comprise five to twenty blades, each having a longitudinal medial slot with intermediate enlargements therein, in which are received the rib 16 and the studs 17, and elongated unsharpened end portions defined by corner notches. In its movement to the right, the uppermost blade is engaged by the ribs 23 of the feed slide, advanced end-wise while held in contact with and guided by the flanges 13 and 14. In its feeding movement, the advancing end of the blade 25 encounters the inclined fulcrum surface 20 of the block 19 and rides up thereon, thus co-operating with the ribs 13 and 14 in transversely bowing the blade. Ejection of the blade in this condition continues until the feed slide 22 is arrested by contact with the stop lugs 24 at the end of the magazine; the blade having fully cleared the last blade-locating stud 17. In this movement, the blade is passed outwardly between the tops of the posts 18 and the under side of the flanges 13 and 14, being maintained always in the transversely bowed condition shown in Fig. 2. The stops 24 are so located that the feed slide is arrested before the blade has been moved entirely beyond the fulcrum surface 20 and the ends of the flanges 13 and 14. In other words, the blade is brought to rest with its rear end clear of stud 17 and held frictionally in transversely bowed condition and so projects freely beyond the end of the magazine in a position where it may be conveniently grasped by the user and withdrawn frictionally from its projecting position.

The magazine of my invention is shown as provided with a safety handle for operating the feed slide in such a manner as to obviate the possibility that the user will cut his fingers in the event that the blade-ejecting or delivering stroke of the feed slide is abruptly or unexpectedly interrupted. In these figures, the feed slide 22 is shown as being provided with a pair of external bearings 26, which are formed by slitting and pressing outwardly the sheet material of the feed

slide. In these bearings is journalled a wire handle 27 having a cross piece 28 forming a hinge connection with the bearings 26. The handle exceeds the length of the blade and is provided at its outer free end with a knurled finger-piece 29. When the feed slide 22 is in its initial position, the finger-piece 29 is located in advance of the outer end of the blade to be ejected and in the blade-ejecting operation this relationship is maintained as suggested in Fig. 2. The result is that the user's fingers, grasping the finger-piece 29, are always in advance of the end of the blade. If the feed slide is abruptly arrested, the user's fingers tend to slip off in a forward direction with no tendency to approach the blade.

When the safety handle feature of my invention is embodied in a double-ended magazine, the handle is arranged to be swung 180° between consecutive blade-delivering operations. Accordingly the cross-piece 28 of the handle may be slightly bowed and act as a spring, causing the handle to be thrown either into the horizontal position shown in Figs. 1 and 2 or into an oppositely directed horizontal position when the feed slide is to be moved to deliver a blade from the right-hand end of the magazine. The safety handle is thus held automatically in one position or the other, making the magazine assembly compact at all times and properly locating the handle for operating the feed slide in either direction according to which end of the magazine the blade is to be delivered from.

It will be understood that the safety handle may be usefully employed with or without the fulcrum block 19.

Having thus disclosed my invention and described in detail an illustrative embodiment thereof, I claim as new and desire to secure by Letters Patent:

1. A blade magazine having walls forming an open-end enclosure, inturned flanges at one end thereof, a fulcrum block disclosed below the plane of said flanges, a feed slide movable upon the enclosure for advancing a blade therefrom, and an operating handle movably connected to the feed slide outside the enclosure and being of a length to overlie said fulcrum block when the feed slide occupies its initial position at one end of the enclosure, whereby the fingers of the user engaging the handle move always in advance of a blade as it is ejected from the magazine.

2. A blade magazine having walls forming a rectangular enclosure with a blade exit slot at one end, a feed slide movable back and forth on the enclosure, and a hinged handle, connected to the feed slide externally of the enclosure and being of such length as to overlie substantially the whole enclosure when the feed slide occupies its initial position at one end of the enclosure, whereby the fingers of the user engaging the handle move always in advance of the blade as it is ejected from the magazine.

3. A blade magazine having walls forming a rectangular enclosure with a blade-exit slot at one end, a stack of slotted blades within the magazine, a feed slide movable on the enclosure to advance one blade at a time from the stack outwardly from one end of the enclosure, and an elongated handle connected at its inner end to the feed slide externally of the enclosure and of such length as to overlie a blade as it passes out through the exit slot, whereby the fingers of the user engaging the handle move always in advance of the blade as it is ejected from the magazine.

4. A blade magazine having exit slots at both

ends, a feed slide movable on the magazine to eject blades alternately from its opposite ends, and a handle pivotally connected to the feed slide externally of the enclosure and including means in its said connection for throwing the handle into substantially horizontal position on one side or the other of the feed slide, whereby the fingers of the user engaging the handle move always in advance of the blade as it is ejected from the magazine.

5. A blade magazine having walls forming a rectangular enclosure with a blade exit in one end and an open medial slot in its top, blade positioning means within the enclosure, a stack of blades therein, a feed slide movable to engage the uppermost blade in the stack through the medial slot of the magazine top, and a handle pivotally mounted on the feed slide externally of the enclosure to swing substantially 180°, whereby the fingers of the user engaging the handle move always in advance of the blade as it is ejected from the magazine.

6. A blade magazine having walls forming a rectangular enclosure, a feed slide movable in the top of the magazine and being shaped to engage and feed blades in either of two directions, and a handle pivotally mounted on the feed slide externally of the enclosure and arranged to be swung so as to overlie a blade being advanced in either direction by the feed slide and to extend beyond the end of the blade while it is being fed, whereby the fingers of the user engaging the handle move always in advance of the blade as it is ejected from the magazine.

7. A blade magazine including a walled blade enclosure having an exit opening at one end, blade-locating means inside said enclosure adapted to receive a stack of blades and hold them with their cutting edges spaced from walls of said enclosure, and a manually-operable blade-pushing member slidable in the longitudinal direction of

said blades and having an abutment portion drivingly engageable with the uppermost blade of said stack at a region rearwardly in a longitudinal sense with respect to the leading end portion of the blade-cutting edge, said blade-pushing member including a readily manually graspable pull-portion located externally of the enclosure and adapted to be seized with the user's fingers, said pull-portion extending in advance of said blade cutting-edge, thereby operatively to locate the user's said fingers ahead of said blade cutting-edge during withdrawal of that blade from the magazine.

8. A blade magazine including an elongated walled blade enclosure having exit openings at both ends, blade loading means inside said enclosure adapted to receive a stack of blades and hold them with their cutting edges spaced from walls of said enclosure, and a manually-operable blade-pushing member slidable to-and-fro in the longitudinal direction of said blades to eject blades alternately through said exit openings, said blade-pushing member including a readily manually-graspable pull element pivotally connected to said blade-pushing member externally of the enclosure and adapted to be seized with the user's fingers, said pull element extending in advance of the cutting edge of the blade being ejected during each successive stroke of said blade-pushing member.
